UNITED STATES PATENT OFFICE.

ALBERT P. HUMMEL, OF INDIANAPOLIS, INDIANA.

AUTOMATIC CISTERN-WATER CONTROLLER.

SPECIFICATION forming part of Letters Patent No. 726,063, dated April 21, 1903.

Application filed December 26, 1902. Serial No. 136,673. (No model.)

To all whom it may concern:

Be it known that I, ALBERT P. HUMMEL, a citizen of the United States, residing at Indianapolis, in the county of Marion and State of Indiana, have invented new and useful Improvements in Automatic Cistern-Water Controllers; and I do declare the following to be a full, clear, and exact description of the invention, reference being had to the accompanying drawings, and to the letters and figures of reference marked thereon, which form a part of this specification.

My invention relates to appliances for controlling the water that may flow from the roofs of buildings into cisterns, and it has particular reference to devices that are connected with the spouts that convey the water to the cisterns and also to the overflow and the cut-out spouts.

20 The object of the invention is to provide inexpensive means whereby the foul water that usually flows first after rains may be automatically cut out or prevented from entering the cisterns and also means whereby cisterns may be protected against overflow during long rainy seasons in cases where they have no independent overflow-outlets.

My invention consists in a water-spout provided with branches and gates therefor and 30 automatically-operative means whereby the gates may be controlled by the action of the water that may pass through the spout; and the invention also consists in the novel parts and in the novel combination and arrangement of parts, as hereinafter particularly described and claimed.

Referring to the drawings, Figure 1 is a fragmentary view in elevation, showing one side of the devices that operate the valve for 40 turning out the foul water; Fig. 2, a view in elevation, showing the lower portions of the water-spouts to which my invention is connected, showing the devices in condition to permit the foul water to pass away without 45 entering the cistern; Fig. 3, a fragmentary central vertical sectional view showing the automatic devices for cutting out the foul water arranged so as to permit the clean water to pass to the cistern; Fig. 4, a horizontal 50 sectional view on the line A A, showing the top of the charging-funnel; Fig. 5, a horizon-

tal sectional view on the line B B, showing internal parts; and Fig. 6 a fragmentary vertical sectional view showing the upper portion of the controller for the cut-out gate for 55 the foul water.

Similar reference characters in the drawings indicate like parts.

In construction the principal parts may be composed of tin-plate, and a section of spout 60 or tubing *a* is provided that may be attached to the lower portion of a vertical spout leading from the roof-gutter of a building, the spout-section *a* having a lateral curved branch *b*, to which is connected a vertical branch *c*, 65 adapted to enter a cistern, which is indicated in the drawings in dotted lines 1, the level of the water being assumed to be approximately at 2 and the top of the cistern at 3. The branch *c* has an outlet branch *d*, extending 70 downwardly at an oblique angle therefrom, which is provided with a cut-out gate *e* at the junction of the two branches. The branch *d* has an inlet-tube *f* at the upper side thereof, and in vertical alinement therewith is a duct 75 *g*, connected with the spout *a* and terminating at a point at a suitable distance above the top of the tube *f* for conveying the foul water away from the branch that leads to the cistern, a controlling-gate *h*, attached to a 80 shaft *i*, being mounted at the junction of the spout *a* and the branch *b* for turning the water in either direction. To complete the foul-water duct, I employ a drum *j*, having a bottom *k*, to which is attached a tube *l*, extending 85 through the drum and connecting the tube *f* with the duct *g*, making substantially a continuous duct through the drum from the spout *a* to the branch *d* and thence to the atmosphere. The drum is capable of holding 90 water above the tube *l*, therefore being an annular tank, and has preferably a screen *m*, covering the top thereof about the tube *l*. The tube *l* has a small drain-hole *n*, covered by a screen *o* in the side thereof immediately 95 above the bottom *k* of the drum. The tube *l* has a sliding connection with the tube *f* and the duct *g*, preferably entering the former and extending over the exterior of the latter, so that the annular tank may ascend and descend and still maintain the continuity of the duct therethrough. The screen *m* may be 100

detachable, so that the tank may be cleaned of trash, and also the tube *l* may be detachable from the tube *f* and the duct *g*.

The shaft *i* is provided with a crank-arm *p* at the outside of the spout-junction, and for the purpose of normally holding the gate *h* in a proper position to exclude the foul water from the branch *b*, as indicated in dotted lines in Fig. 2, a spring *q* may be coiled about the shaft *i* and suitably connected thereto and to the spout, or a coiled spring *r* may be employed indirectly for the same purpose, in the present case this spring being connected to the annular tank and also to the branch *b*, the tank being connected by a link *s* with the arm *p*, and thereby with the shaft *i*, so that while the spring *r* normally supports the tank the gate *h* is also held so as to close the branch *b*. In case the spring *q* is employed it will support the tank by means of the arm *p* and the link *s*.

In order to automatically operate the gate *h*, a charging-duct *t* is connected with the spout *a* (or permissibly with its extension *g*) and with the annular tank, the upper end of the duct-tube having a funnel-shaped mouth *u* within the spout, provided with an inclined screen *v* to prevent choking of the duct by leaves, &c.

For controlling the amount of water that may be desired to remain in the cistern the shaft *w* of the gate *e* is provided with a crank-arm *x*, to which is connected a rod *y*, having a float *4* at the lower end thereof, the rod extending into the cistern and the float situated so as to be floated when the water may reach the desired level in the cistern, the elevation of the float causing the gate *e* to turn the water from the spout branch *c* into the branch *d*.

In order to avoid injury to the annular tank should water therein freeze, a suitable number of yielding bars *5*, preferably composed of soft wood, are attached to the screen *m* and extend to the bottom *k* of the tank.

It should be understood that various modifications may fairly be made in the details of construction within the scope of my invention—as, for instance, the tube *l* need not extend above the screen *m*, although herein shown elongated for illustrative purposes, and the springs *q* or *r* may be mounted in various ways to accomplish the same ends.

In practical use the annular tank for governing the gate *h* will be elevated by the springs *q* or *r* to its highest possible position, when the gate *h* will close the branch *b*. The water in the cistern being low enough will permit the weight of the float *4* to hold the gate *e* in a position designed to close the opening to the branch *d*. If now the water begins to flow down the spout *a*, it may be supposed to be unclean by reason of soot and dust on the roof of the building, and, as designed, it will pass through the branch *g*, the tube *l*, the inlet-tube *f*, and out through the branch *d* without entering the cistern. Some of the

foul water in its passage will enter the duct *t* through the screen *v* and pass into the annular tank in greater quantity than may pass out of the drain-hole *n*, the latter being the smaller, and the water will gradually accumulate until the springs *q* or *r* become overbalanced, when, as the foul water may be presumed to have passed away, the tank will descend and open the gate *h* to the branch *b*, closing the branch or duct *g*, permitting the clean water to pass into the cistern, some of the clean water still entering the tank and holding it down. When the water stops flowing in the spout *a*, obviously no more will enter the tank, and what may be there will slowly pass through the hole *n* and out the branch *d*, permitting the spring to again elevate the tank and close the gate *h* to the branch *b*. Should the cistern become as full as intended that it should, the float *4* will rise on the water and open the gate *e* to the branch *d* and cause the excess water to pass away ungathered.

Having thus described my invention, what I claim as new is—

1. An automatic cistern-water controller including a spout having a cistern branch and having also a terminating branch extending beyond the junction of the cistern branch with the spout, a gate at the junction of the cistern branch, a movable tube connecting the terminating branch and having a tank attached thereto, a charging-duct communicating with the spout and also with the tank, a spring normally supporting the tank and the movable tube, an arm operatively connected with the gate and also with the tank, an outlet branch in connection with the movable tube, and means whereby the outlet branch may be supported fixedly.

2. An automatic cistern-water controller including a spout having a cistern branch and having also a terminating branch extending beyond the junction of the cistern branch with the spout, a gate at the junction of the cistern branch, a movable tank operatively connected with the gate, a spring normally supporting the tank, a movable tube connected with the terminating branch and secured to the tank and having a drain-hole situated in a plane at the upper side of the bottom of the tank, a charging-duct communicating with the spout and also with the tank, an outlet branch in connection with the movable tube, and means whereby the outlet branch may be fixedly supported.

3. An automatic cistern-water controller comprising a spout having a cistern branch and also a terminating branch in a plane above the cistern, an outlet branch connected to the cistern branch and having a vertical inlet-tube, a movable tube connecting the terminating branch and the inlet-tube and having a tank attached thereto, a gate at the junction of the cistern branch and the terminating branch, a charging-duct communicating between the spout and the tank, a spring

normally supporting the tank and the movable tube, an arm connected with the gate and also operatively connected with the tank, a cut-out gate at the junction of the cistern 5 branch and the overflow branch, and a float connected with the cut-out gate.

4. An automatic cistern - water controller comprising a spout having branches, an overflow-duct connected with the branches, a 10 poised tank having a drain-hole, a charging-duct for the tank, a gate at the junction of

the branches connected operatively with the tank, yielding bars in the tank, a cut-out gate at the junction of the overflow-duct with one of the branches and having a float connected therewith, and a poised device for the tank. 15

In testimony whereof I affix my signature in presence of two witnesses.
